UNITED STATES PATENT OFFICE.

HARRY F. SMITH, OF LEXINGTON, OHIO, ASSIGNOR, BY MESNE ASSIGNMENTS, TO THE GAS RESEARCH COMPANY, OF DAYTON, OHIO, A CORPORATION OF OHIO.

STOKER.

1,373,265.

Specification of Letters Patent. Patented Mar. 29, 1921.

Application filed May 31, 1917. Serial No. 171,949.

To all whom it may concern:

Be it known that I, HARRY F. SMITH, a citizen of the United States of America, residing at Lexington, county of Richland, 5 and State of Ohio, have invented certain new and useful Improvements in Stokers, of which the following is a full, clear, and exact description.

This invention relates to mechanical stokers and more particularly to automatically operated mechanical stokers for introducing fuel into a fire box or gas producer at any desired, predetermined rate; and the object of the invention is to provide a mechanical 15 stoker which is completely automatic in its operation, which introduces fuel onto the grate at any regular and predetermined rate of speed desired, which is so constructed as to prevent any damage accruing to the apparatus from choking or jamming of the stoking mechanism and which is so constructed as at all times to prevent the escape therethrough of gases from the fire box. In carrying my invention into effect I employ 20 a stoking mechanism comprising a rotatably mounted ported disk which is actuated to bring its ports successively into register with a source of fuel supply for receiving therein charges of fuel and with a passage 25 whereby the charges of fuel are admitted to the interior of the fire box or gas producer. The disk is operated by mechanical means which means is in turn driven from any suitable power source, the driving means 30 comprising a friction clutch automatically allowing of stopping the operating means 35 without shutting off the driving power transmitted thereto.

The apparatus forming the subject of my 40 invention is identical with the stoking mechanism disclosed in my copending application for improvements in gas producers filed May 23, 1917 and bearing Serial Number 170,493 and, as in that application, is 45 illustrated in the drawings as attached to a gas producer for feeding fuel into the generating chamber thereof. It is obvious, however, that stoking mechanism of this character is just as capable of use in connection with various other types of apparatus, and consequently, although as a preferred adaptation and for purposes of easier 50 description I have shown it as attached to

a gas producer. I do not limit myself to such disclosure.

In the drawings, in which like reference characters designate like parts throughout the several views thereof:

Figure 1 is a side elevation of a portion of a gas producer with my improved stoking mechanism carried thereby.

Fig. 2 is a plan view of the stoking mechanism.

Fig. 3 is a longitudinal sectional view along the line 3—3 of Fig. 2.

Fig. 4 is a front elevational view of a portion of a gas producer with the stoking mechanism attached thereto.

Fig. 5 is a sectional view through the friction clutch.

Fig. 6 is a sectional view through a different form of friction clutch.

In the drawings 1 designates a producer shell having attached to the top and near the front thereof a stoker designated generally by the numeral 2.

The lower part of the stoker 2 consists of a base section 3 rigidly attached to the top of the producer shell. Extending upwardly from the center of this base section 80 is an extension 4 having at the upper end thereof a smaller extension 5. The base section has therethrough a port 6 which registers with a similarly shaped port 7 extending through the top of the producer shell and opening into the interior thereof, whereby any fuel introduced into the port 6 will pass through the port 7 into the generating chamber of the producer and be deposited upon the fuel bed therein. The 90 port 6 has pivotally mounted therein a deflector 8 actuated by a handle 9. This handle 9 is mounted in the base section 3, its inner end being loosely connected to the deflector 8, and is held in position by means of a groove 10 therein which has co-operating therewith an adjustable pin 11 extending through that part of the base section bearing the handle. Pivotally attached to the handle 9 is a spring pressed locking arm 100 12 which co-operates with a properly notched portion 13^a carried by the base section 3 for locking the deflector in any desired position. It is evident that by properly adjusting the deflector 8 fuel passing through the 105 port 6 may be directed entirely to one side

or the other thereof, or may be fed in two separate streams to opposite sides of the deflector, the relative proportion of fuel fed to each side being subject to ready variation.

Mounted upon the extension 4 and rotatable thereupon is a flat disk member 13 which seats upon the top surface of the base section 3. This disk member has therethrough 10 four ports 14 equidistantly spaced. Extending around the outer surface of the disk member is a series of teeth 15 which coöperate with an actuating pawl 16.

Carried by the smaller extension 5 is a 15 hopper plate or member 17 which seats upon the top surface of the disk 13 and has attached thereto a hopper 18. The hopper plate 17 is rigidly connected to the extension 5 by means of a bolt 20, and the extension 20 3 and the recess 19 in the hopper plate co-operating therewith are so shaped that when secured in position rotation of the plate 17 relative to the base section 3 is prevented. At the lower end of the hopper 18 is a port 25 21 similar in shape and size to the ports 14 in the disk member. The base member and the hopper plate are so positioned that the port 6 and the port 21 are out of alinement with each other, and the contacting surfaces 30 of the members 3, 13 and 17 are so formed that tight joints exist between them. In this manner leakage of gas from the producer or fire box into the atmosphere or of air from outside to the inside thereof is prevented. The recess 19 is deeper than the extension 5 so that by properly manipulating the bolt 20 wear of the contacting surfaces 35 of the members 3, 13 and 17 may be compensated for and tightness of the joints 40 therebetween insured. By so compensating for wear of the contacting surfaces not only is the leakage of gas prevented, but also the working of fuel or foreign substances between the parts of the stoking mechanism 45 to cause jamming thereof is prevented. In the hopper plate 17 is a poke hole 22 in alinement with the ports 6 and 7 so that access may be had therethrough to the inside 50 of the generating chamber. Covering this poke hole 22 is a pivoted plate 23 so mounted that it may be swung aside when such access is desired.

As stated above the disk member 13 has coöperating therewith a pawl 16. This pawl 55 is carried by a member 24, pivoted at 25 to a rocker arm 26 which arm is in turn pivoted at 27 to a member 28 rigidly attached to the producer shell or to some portion of the stoking mechanism or some part of the apparatus with which such stoker is being 60 used. Situated between the pawl and the member 24 is a spring 29 so positioned as to hold the pawl constantly in contact with the teeth 15. Because of its double pivotal 65 connection it is evident that the pawl is

capable of both vertical and horizontal movement. Mounted in suitable bearings on the front of the producer shell is a shaft 30 which carries thereon an eccentric roller 31. The shaft 30 is rotatably driven through the 70 medium of a gear 32, mounted on one end thereof, by means of a rotating shaft 33 carrying thereon a smaller gear 34 which meshes with the larger gear 32. The shaft 33 receives its rotary motion through the 75 medium of a friction clutch 35 which is positively driven from any suitable power source. Mounted on the lower end of the rocker arm is a roller 36 which is held in frictional contact with the eccentric roller 31 80 by means of a spring 37 one end of which is attached to the hook 38 carried by the rocker arm 26 and the other end to some stationary part of the apparatus, as at 39.

The friction clutch which I prefer to use 85 for driving the shaft 33 is that form shown in Fig. 5. This clutch comprises a disk member 40 having a hub portion 41 extending therefrom adapted to fit upon one end of the shaft 33 and to be tightly keyed 90 thereto. Carried in one face of the disk 40 is a series of wooden pins 42. Rotatably mounted upon the hub 41 is a cup shaped member 43 one wall 44 of which is adapted to overlie and inclose the disk member 40. Rigidly attached to the wall 44 at the open 95 end thereof is a cap 45. The cup member 43 and the cap 45 when attached together form a housing completely inclosing the disk member 40 which housing is mounted upon 100 the hub 41 and is capable of rotary motion relative thereto, and to the disk 40. Projecting from the end of the cap 45 and in alinement with the shaft 33 is an internally threaded hollow extension 46 normally 105 closed by a threaded plug 47 held in position by a set screw 48. Located in the cap 45 is a helical spring 49 one end of which bears against the plug 47 and the other end of which surrounds the end of shaft 33 and 110 bears against the disk 40. By adjusting the plug 47 the spring 49 may be placed under any desired tension so as to force the cap 45 and the cup member 43 longitudinally of the shaft 33 to bring the inner wall of 115 the cup member into frictional contact with the wooden pins 42. The cup member 43 has the outer surface of its wall 44 cylindrical in form and the periphery thereof properly fashioned for serving as a driving pulley. With the spring 48 under sufficient tension, so as to produce the requisite 120 amount of friction between the cup member 43 and the wooden pins 42, it is evident that power applied to the member 43, as by means of a belt passing around the periphery of portion 44 and driven from any suitable power source, and causing rotation thereof, will also produce rotation of shaft 33. It is 125 also evident that if for any reason the shaft 130

33 is prevented from turning, as would be the case if the disk 13 were to jam because of becoming choked with coal or because of some foreign material wedging between it and some other portion of the stoking mechanism, the apparatus would not be broken. If such retardation of the shaft 33 was sufficiently strong, the cup member 43 with its attached parts would continue to rotate but 10 would slide over the wooden pins 42 without giving rise to a sufficiently strong driving force tending to rotate the shaft 43 to actually rotate that shaft against the retarding force in the stoking mechanism and to 15 thus cause damage thereto.

Fig. 6 illustrates a different form of friction clutch. This clutch consists of a cone member 50 rigidly keyed to the shaft 51 which has a smaller extension 52 at one end 20 thereof. Rotatably mounted upon this smaller extension 52 is a disk member 53 held thereupon by the nut 54 and lock nut 55. Extending from the face of the disk member 53 so as to overlie the cone shaped 25 member 50 is a series of pins 56 each of which carries thereon a helical spring 57. Also carried by the pins 56 is a plate 59 having holes therein adapted to pass over the pins 56. This plate is placed upon the pins 30 56 after the springs 57 are in position so that when properly assembled these springs bear at their opposite ends upon disk 53 and the plate 59. Rotatably mounted upon the shaft 51 is a pulley 60 the hub 61 of which 35 has a conical bore adapted to coöperate with the conical periphery of member 50. The hub 61 has thereon a rib 62 against which the ring 59 is adapted to press when the clutch is assembled. By properly positioning the disk 53 on the shaft extension 40 52, which positioning may be easily accomplished by means of the nut 54 and the lock nut 55, the spring 57 may be placed under such tension as to force the pulley 60 toward 45 the conical member 50 with sufficient force to produce any desired amount of friction between the conical surfaces of the members 50 and 62. It is evident therefore that any power applied to the pulley 60 to rotate it 50 will also rotate the shaft 51, which shaft is a driving shaft for such a stoker mechanism as described above. And it is also evident that this friction clutch will operate in precisely the manner described above to prevent 55 breaking of the elements of the stoking mechanism in case those elements become jammed.

In operation of the device fuel is fed into the hopper 18 in such manner as to keep 60 that hopper constantly supplied. Regularly progressive, rotary motion is imparted to the disk by the frictionally driven actuating mechanism. As the disk rotates about the extension 4 the ports therethrough register successively with the port 21 receiving

at such times a charge of fuel from the hopper. As the rotation of the disk continues the charged ports are moved into register with the port 6 in the base member and the charges of fuel therein are discharged therethrough onto the grate or fuel bed. If for any reason, as by the jamming of some foreign material between the disk and the base member or the hopper member, rotation of the disk is impeded or completely stopped, no 70 damage is caused to the apparatus because of the friction clutch. It is evident that if there is a sufficient retardation to the rotary movement of the disk, such retardation will be transmitted to the driving mechanism for 75 the disk, which mechanism will be retarded in accordance with the retarding of the disk. In such circumstances the pulley member 43 will continue to rotate inasmuch as the driving power is still being applied thereto, but 80 will slip over the pins 42 and thus permit, if circumstances demand, the disk 13 and its actuating mechanism to even come to a complete stop.

It is evident from the above that I have 90 devised a stoking mechanism which is completely automatic in its action and which is adapted to feed fuel at any desired regular, predetermined rate, and that I have devised a device in which the wear of the various parts of the feeding mechanism is 95 readily taken care of so that there will be little or no tendency for leakage of gases therethrough, or for the jamming of materials to cause a binding or breaking of the 100 parts thereof.

What I claim as my invention, and desire to secure by Letters Patent, is:

1. In a gas producer or the like, the combination in a fuel feeding device, of a stationary base member having a port therethrough; a stationary hopper member having a port therethrough, said ports being out of alinement; a rotatable disk member intermediate said base member and said hopper member, said disk member having a port therethrough adapted to register with either of the aforesaid ports, a plurality of peripheral teeth thereon; a pawl adapted for engagement with said teeth to cause rotation 105 of the disk member; and mechanism for actuating said pawl, said mechanism including a friction clutch.

2. In a gas producer or the like, the combination in a fuel feeding device, of a stationary base member having a port therethrough; a stationary hopper member having a port therethrough, said ports being out of alinement; a rotatable disk member intermediate said base member and said hopper member, said disk member having a port therethrough adapted to register with either of the aforesaid ports, a plurality of peripheral teeth thereon; a pawl adapted for engagement with said teeth to cause rotation 110 115 120 125 130 of the disk member; and mechanism for actuating said pawl, said mechanism including a friction clutch.

- of the disk member; mechanism for actuating said pawl; and means for maintaining the hopper, disk, and base members in substantially gas-tight contact.
- 5 3. In a gas producer or the like, the combination in a fuel feeding device, of a stationary base member having a port therethrough; a stationary hopper member having a port therethrough, said ports being
10 out of alinement; a rotatable disk member intermediate said base member and said hop-

per member, said disk member having a port therethrough adapted to register with either of the aforesaid ports, a plurality of peripheral teeth thereon; a pawl adapted for 15 engagement with said teeth to cause rotation of the disk member; mechanism for actuating said pawl; a deflector within the base member port, and means for holding said deflector in any desired position. 20

In testimony whereof I affix my signature.
HARRY F. SMITH.
